US0D1053861S

(12) **United States Design Patent** (10) **Patent No.:** **US D1,053,861 S**
(45) **Date of Patent:** **** Dec. 10, 2024**

(54) **MINI COMPUTER**

(71) Applicant: **Shenzhen Chuangyingxin Industrial Co., Ltd.**, Shenzhen (CN)

(72) Inventor: **Tao Wang**, Shenzhen (CN)

(73) Assignee: **Shenzhen Chuangyingxin Industrial Co., Ltd.**, Shenzhen (CN)

(**) Term: **15 Years**

(21) Appl. No.: **29/874,960**

(22) Filed: **Apr. 27, 2023**

(30) **Foreign Application Priority Data**

Apr. 18, 2023 (EM) 015018616-0001

(51) **LOC (14) Cl.** **14-02**

(52) **U.S. Cl.**

USPC **D14/314**

(58) **Field of Classification Search**

(57) **CLAIM**

The ornamental design for a mini computer, as shown and described.

DESCRIPTION

FIG. 1 is a rear, right and top perspective view of a mini computer, showing my new design;

FIG. 2 is a front, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the mini computer that form no part of the claimed design.

1 Claim, 8 Drawing Sheets
